REEL FOR SEAT BELT

William B. Hixenbaugh, Maple Heights, Ohio, assignor to
The Durox Company, a corporation of Ohio

Filed Jan. 27, 1964, Ser. No. 78,368

Term of patent 14 years

(Cl. D41—1)

FIG. 1

FIG. 2

FIG. 3

FIG. 4

The dominant features of my design are shown in full lines.

I claim:

The ornamental design for a reel for seat belt, substantially as shown and described.
